UNITED STATES PATENT OFFICE.

ARLINGTON EARL RISHEL, OF SEATTLE, WASHINGTON.

ELECTRIC SWITCH.

1,337,961.

Specification of Letters Patent. Patented Apr. 20, 1920.

Application filed November 27, 1918. Serial No. 264,399.

To all whom it may concern:

Be it known that I, ARLINGTON EARL RISHEL, a citizen of the United States, residing at Seattle, in the county of King and State of Washington, have invented certain new and useful Improvements in Electric Switches; and I do declare the following to be a full, clear, and exact description of the invention, such as will enable others skilled in the art to which it appertains to make and use the same.

This invention relates generally to electric switches.

One object of the invention is to provide an improved longitudinally movable switch bar and an improved means for mounting the same.

A further object of the invention is to provide a device of this character which will be simple, strong, durable and inexpensive in construction, efficient and reliable in operation, and well adapted to the purpose for which it is designed.

With these and numerous other objects in view, the invention consists of certain novel features of construction, and the combination and arrangement of parts as will be hereinafter fully described and claimed.

In the accompanying drawings forming a part of the application and in which similar reference characters are used to designate like parts throughout the several views:—

Figure 1 is a side elevation of a device constructed in accordance with this invention, showing the switch bar in its first position;

Fig. 2 is a top plan view of the device;

Fig. 3 is an end view of the same;

Fig. 4 is a side elevation of the device showing the switch bar in its second position;

Fig. 5 is a similar view showing the switch bar in its third position; and

Fig. 6 is a transverse sectional view taken on the plane indicated by the line 6—6 of Fig. 1.

Referring more particularly to the drawings; the numeral 1 designates a rectangular base adapted to be placed on a table or other flat support. Formed integrally with the base 1 and rising from the same midway of its width is an upright supporting plate or member 2 having at one end thereof an opening 3 of a size sufficient to receive the rear end of an ordinary alarm clock 4 thereinto. The alarm clock 4 is provided with the

usual alarm winding key 5, and the shaft 6 of this key is provided with a pinion 7, the purpose of which will be hereinafter described. In the type of clock shown in the drawings, the key 5, and therefore the shaft 6 and pinion 7, are rotated in an anti-clockwise direction for winding the alarm mechanism, and from this it will be seen that when the alarm mechanism is tripped, these parts move in a clockwise direction. If, however, the alarm clock used is provided with parts which rotate in a direction reverse to that of the clock herein shown and described, then said clock is mounted at the opposite end of the member 2 from that shown.

Revolutely mounted upon suitable studs or pivots 8, fixed to the supporting member 2, is a pair of peripherally grooved contact rollers or wheels 9. These studs 8 are provided with binding posts 10 to which electric conductors 11 are connected. Pivoted intermediate their ends to the member 2 by means of a pair of screws 12 are levers 13. One of the arms of each lever 13 is provided with a combined bearing stud and binding post 14, and a second pair of peripherally grooved contact rollers or wheels 15 is pivotally mounted on these elements 14. The other ends of the levers 13 are offset laterally and provided with apertures 16 to which the hooked ends of a pair of coiled springs 17 are connected. The other ends of these coiled springs 17 are hooked around or otherwise secured to studs 18 projecting from the member 2.

As clearly shown in Figs. 1 and 4 of the drawings, the axis of each wheel 15 lies in the same vertical plane with that of the corresponding wheel 9, and the axes of the rollers of each pair lie in a horizontal plane parallel with the plane of the other pair. Longitudinally movable between these pairs of wheels is a switch bar 19. No other means of support for the bar 19 is necessary inasmuch as the yieldable mounting of the rollers 15 holds said bar between the latter and the rollers 9 so that the same will not move except in a longitudinal direction.

This bar 19 is preferably composed of a pair of longitudinal strips of insulating or non-conducting material 20 having disposed between the same and riveted thereto a trio of non-conducting plates 21, 22 and 23 and a pair of conducting plates 24 and 25 arranged in alternate series, that is, one con-

ducting plate is disposed between the central non-conducting plate 22 and each of the end non-conducting plates 21 and 23. The plates 21, 22, 23, 24, and 25 are greater in width than are the strips 20 and project beyond the edges of the latter, so that the edges of the bar 19 as a whole, are reduced in thickness to afford an efficient engagement with the grooved rollers 9 and 15.

- 10 Riveted to the strips 20 and disposed between the same is a plate 26, one of the edges of which is formed into a series of teeth to provide a rack 27 for engagement with the aforesaid pinion 7. The numeral 15 28 designates a guide roller, which is mounted upon the member 2 adjacent the opening 3 and in contact with the edge of the bar 19 opposite to the edge on which is disposed the rack 27. The purpose of this 20 roller will appear hereinafter.

In Fig. 1 of the drawings, the bar 19 is shown in its first position and from this it may be seen that the non-conducting plates 22 and 23 are in contact with the rollers 9 and 15 and consequently no current will pass from the line wires 11 through the rollers 9 to the rollers 15 and then through the conductors 29 connected to the binding posts 14. When it is desired to close the 30 circuit through the conductors 11 and 29 automatically, the bar 19 is first moved manually to the left so that the rack 27 becomes disengaged from the pinion 7, and the alarm winding key 5 is turned in an 35 anti-clockwise direction to wind the alarm mechanism of the clock. The bar 19 is then moved so that the rack again engages the pinion 7 and until it is in its first position. When the alarm mechanism is released au- 40 tomatically at the desired hour, the shaft 6 and pinion 7 will be rotated in a clockwise direction, and the bar 19 will be moved toward the right to its second or circuit-closing position in which the conducting plates 45 24 and 25 are in contact with the rollers 9 and 15. To limit the movement of the bar 19 to its second position, the bar 19 is provided at its outer end with a pin or stud 30, the latter engaging the laterally bent end 50 31 of a pivoted arm or lever 32, which acts in the capacity of a stop a stud or abutment 33, on the support 2, coacting with the lever for this purpose in an obvious manner. This lever 32 is, however, capable of being 55 swung into an ineffective position which is necessary when it is desired that the circuit through the conductors 11 and 29 is to be alternately opened and closed by a single movement of the bar 19.

- 60 When this last mentioned result is desired, the lever 32 is swung manually to its ineffective position and the alarm set. When the alarm mechanism is tripped, the bar 19 will, as before, be moved longitudinally toward the right, until the pinion 7 en-

gages the inner end of the rack 27. The guide 28 prevents the bar 19 from being moved laterally, and consequently the pinion 7 will engage the portion of the plate 26 having no teeth and thereby limit the movement of said bar 19 to its third position, that is, in a position where the non-conducting plates 21 and 22 are engaged by the rollers 9 and 15.

A switch constructed in accordance with 75 this invention will be found very desirable for use in connection with an alarm clock, as shown and described, for automatically breaking the circuit through the lights in show windows of stores, for it is only necessary to turn on the lights and set the alarm of the clock to trip at the desired hour. Many other uses may be allotted to the invention, and it is not necessary to herein 80 enumerate them.

85 As various changes in form, proportion, and in the minor details of construction, may be resorted to without departing from the spirit of this invention, I do not wish to be limited to the construction herein 90 shown and described other than that set forth in the appended claims.

I claim:—

1. In an electric switch, a support, two pairs of peripherally grooved wheels of conducting material having their axes mounted on said support, a switch-bar comprising two insulating strips, and a series of conducting plates and insulating plates arranged alternately and in alinement between said 95 strips and secured thereto, two opposite edges of said series of plates projecting laterally beyond the corresponding edges of said strips, said bar being seated between said pairs of wheels and having said opposite edges of said series extending into the peripheral grooves of the wheels, the wheels and the alternate plates being arranged and spaced in such mutual relation that when two opposite wheels engage with one of 100 said plates, the other two opposite wheels engage with another plate of similar conductive character, said bar being movable longitudinally to change the wheels 105 from their contact with the conducting plates to their contact with the insulating plates and vice versa, each of said wheels being electrically connectible with a conducting element of an electric circuit.

2. In an electric switch, a support, two 120 pairs of wheels of conducting material pivotally mounted on said support, a switch-bar comprising a series of plates of conducting and insulating materials of equal width arranged and secured alternately and 125 in alinement to form the bar, said bar being seated to move longitudinally between the pairs of wheels, the wheels and alternate plates being arranged and spaced in such mutual relation that when two opposite 130

wheels engage with one of said alternate plates, the other two opposite wheels engage with another plate of similar electrical character, each of said wheels being electrically connectible with a conducting element of an electric circuit, a stud on and extending laterally from said bar, a lever pivotally mounted on said support and being rotatable on its pivot into and out of the path of said stud, and an abutment in the path of movement of the lever and being effective to hold the lever against movement along said path in one direction, the relative positions of the lever and wheels and plates and stud being such that the lever ¹⁵ will stop the bar in a closed-switch position, substantially as specified.

In testimony whereof I have hereunto set my hand.

ARLINGTON EARL RISHEL.
